UNITED STATES PATENT OFFICE.

GEORGE H. CHATILLON, OF NEW YORK, N. Y.

CONCEALING MECHANISM FOR SCALES, REGISTERS, &c.

SPECIFICATION forming part of Letters Patent No. 364,478, dated June 7, 1887.

Application filed February 17, 1887. Serial No. 227,911. (No model.)

To all whom it may concern:

Be it known that I, GEORGE H. CHATILLON, a citizen of the United States, residing at New York, in the county and State of New York, have invented new and useful Improvements in Concealing Mechanism for Scales, Registers, and other Articles, of which the following is a specification.

This invention relates to improvements in concealing mechanisms, as set forth in the following specification and claims, and illustrated in the accompanying drawings, in which—

Figure 1 is a section in the plane xx , Fig. 5, looking in the direction of arrow 1. Fig. 2 is a section in the plane yy , Fig. 6, looking in the direction of arrow 2. Fig. 3 is a broken side view, partly in section, showing the mechanism applied to a platform-scale. Fig. 4 is a face view of a dial and an index. Fig. 5 is a section in the plane zz , Fig. 1, looking in the direction of arrow 3. Fig. 6 is a section in the plane $x'x'$, Fig. 2, looking in the direction of arrow 4. Figs. 7, 8, and 9 show a modification.

Similar letters indicate corresponding parts. In the drawings, the letter A designates a face-plate held in position by suitable means, such as a case or support, R. In the face-plate is an opening or sight, B. A concealing-plate, C, is adapted to move about a pivot or point of oscillation, D. The opening B has various points at varying distances from the point of oscillation D. As seen in Fig. 6, for example, one extremity of the opening B is nearer to the point of oscillation than the other extremity.

The outline of the concealing-plate C corresponds, in substance, to the outline of the opening B. When the plate C is in one position—as, for example, in Fig. 5, where the concealing-plate C abuts against the stop S—then the opening B is closed or obscured by said concealing-plate. When the concealing-plate C is in another position—as, for example, in Fig. 6, where the concealing-plate C abuts against the stop T—the plate C leaves the passage or sight through the opening B unobstructed.

The stops S T are suitably applied—as, for example, to the face-plate A. In the drawings, the stop T is shown as serving for a bear-

ing or support for the pivot D. It will thus be noticed that by oscillating the concealing-plate C about the pivot or point of oscillation D the opening B can be either closed or opened. By making the concealing-plate C approximately annular or partly annular, as seen in Figs. 5 and 6, the concealing-plate C will be light. The concealing-plate C is so adjusted as to tend toward its closing or concealing position, as shown in Fig. 5. A weight, L, properly applied, is shown as causing the plate C to tend toward its closing position.

The concealing-plate C is provided with a receiving device, such as a cup, E, adapted to receive an actuator or weight, F—such, for example, as a coin. A channel or guide, G, extending to the exterior of the apparatus, may serve to bring the weight F to the receiving device E. By having the receiving device E receive a sufficiently heavy actuator or weight, F, the concealing device C will be carried by the actuator or weight F to its open or revealing position. (Shown in Fig. 6.) As seen in Fig. 6, the receiving device E is so shaped as to retain the weight F and hold the plate C in its revealing position until the weight F is removed from the receiving device E. An arm or ejector, J, is adapted to remove the weight F from the receiving device E. The ejector J is shown as applied to the concealing-plate C.

In the drawings is shown a hand or index, I, adapted to travel from and toward a starting-point marked o on a dial, H. The return of the index I to its starting-point causes the index to strike a lug, K, on the ejector J. The ejector J is thus actuated and removes the weight F and receiving device E, when the concealing-plate C returns to its concealing or covering position.

In Fig. 3 the concealing mechanism is shown as applied to a scale. By placing a weight on the scale-platform Q the rod P, connected to the platform Q, will actuate the index I by means of a rack, O, on the rod P engaging a pinion, N, on the shaft M of the index I. The index I thus is caused to travel from its starting-point o, so as to indicate on the dial H the weight of the object resting on the platform Q. By now dropping a weight, F, such as a coin, into the cup or receiving device E, the concealing-plate C will be oscillated so as to allow

the index I and the scale U on the dial H to be seen through the opening B. On removing the weight from the platform Q the index I will return to its starting-point o, thereby striking the lug K and actuating the ejector J. The concealing-plate C is thus returned to its closing or concealing position. Of course I do not limit myself to the application of this concealing mechanism to scales, as such concealing device may be applied to various mechanisms—such, for example, as tallying or scoring mechanisms or registers of various kinds.

The weights or coins F ejected from the receiving device E may be caused to fall onto a suitable support or flooring, V, Fig. 3, whence they may be removed at suitable times.

Fig. 7 shows a face view of a modification with the opening or sight B in the face plate 25 A closed. In Fig. 8 the opening B is open.

Fig. 8 is a section in the plane y' y', Fig. 9, looking in the direction of arrow 5.

Fig. 9 is a section in the plane z' z', Fig. 8, looking in the direction of arrow 6.

25 In the modification shown in Figs. 7, 8, and 9 the scale U is connected to the concealing-plate C. When the concealing-plate C is in the position shown in Fig. 8 the scale U is not visible through the opening or sight B. To bring the scale U into view, an actuator or weight is caused to act upon the receiving device E, whereby the concealing-plate and scale U are carried to such a position that the scale U becomes visible through the opening B.

35 As seen in Fig. 9, the index I in this modification is made with two sections or hands, I I, one exterior of the case R and one interior of the case R. When the index returns to its starting-point the inner section, I, of the index acts on the ejector J to remove the actuator from the receiving device E, as already explained.

In the modification, Fig. 9, the support or bearing D of the concealing-plate C is shown 45 as continuous with the axle or bearing M of the index I. The opening or sight B can be closed or protected by transparent material—such, for example, as glass or mica.

What I claim as new, and desire to secure 50 by Letters Patent, is—

1. The combination, with a face-plate, A, of a concealing-plate, C, adapted to move about a point of oscillation, D, and mechanism, substantially as described, for actuating the concealing-plate C, said face-plate A being provided with an opening or sight, B, various points of said opening being situated at varying distances from the point of oscillation D, and the concealing-plate being provided with an outline 55 made in conformity to the shape of said opening B, substantially as set forth.

2. The combination, with a face-plate, A, of a concealing-plate, C, adapted to move about a point of oscillation, D, said concealing-plate 60 C being adjusted to tend toward its concealing position and being provided with a receiving device, E, adapted to receive an actu-

ator or weight for carrying the concealing-plate C to its revealing position, said face-plate A being provided with an opening or sight, B, various points of said opening being situated at varying distances from the point of oscillation D, and the concealing-plate being provided with an outline made in conformity to the shape of said opening B, substantially as set forth. 75

3. The combination, with a face-plate, A, of a concealing-plate, C, adapted to move about a point of oscillation, D, said concealing-plate C being adjusted to tend toward its concealing position and being provided with a receiving device, E, and with an ejector, J, said face-plate A being provided with an opening or sight, B, various points of said opening being situated at varying distances from the point of oscillation D, and the concealing-plate being provided with an outline made in conformity to the shape of said opening B, substantially as set forth. 80

4. The combination, with a scale, U, having 90 an index, I, of a face-plate, A, and a concealing-plate, C, adapted to move about a point of oscillation, D, said concealing-plate C being adjusted to tend toward its concealing position and being provided with a receiving device, E, and with an ejector, J, said ejector being adapted to be actuated by the index I, said face-plate A being provided with an opening or sight, B, various points of said opening being situated at varying distances from the point of oscillation D, and the concealing-plate being provided with an outline made in conformity to the shape of said opening B, substantially as set forth. 95

5. The combination, with a scale, U, having 105 an index, I, of a face-plate, A, provided with an opening or sight, B, and a concealing-plate, C, adapted to cover and uncover said opening B, said concealing-plate C being adjusted to tend toward its concealing or covering position and being provided with a receiving device, E, and with an ejector, J, said ejector being adapted to be actuated by the index I, substantially as set forth. 110

6. The combination, with a scale, U, having 115 an index, I, of a face-plate, A, provided with an opening or sight, B, and a concealing-plate, C, adapted to cover and uncover said opening B, said concealing-plate C being adapted to be actuated by an actuator or weight, F, and by the index I, substantially as set forth. 120

7. The combination, with a scale, U, having an index, I, and index-actuating mechanism, substantially as described, of a face-plate, A, provided with an opening or sight, B, and a 125 concealing-plate, C, adapted to cover and uncover said opening B, said concealing-plate C being adapted to be actuated by an actuator or weight, F, and by the index-actuating mechanism, substantially as set forth.

8. The combination, with an index, I, and a face-plate, A, provided with an opening or sight, B, of a concealing-plate, C, adapted to carry a scale, U, to and from the opening or 130

sight B, said concealing-plate C being also adapted to be actuated by an actuator or weight, F, and by an index, I, substantially as set forth.

9. The combination, with an index, I, and index-actuating mechanism, substantially as described, of a face-plate, A, provided with an opening or sight, B; and a concealing-plate, C, adapted to carry a scale, U, to and from the opening or sight B, said concealing-plate

C being also adapted to be actuated by an actuator or weight, F, and by the index-actuating mechanism, substantially as set forth.

In testimony whereof I have hereunto set my hand and seal in the presence of two subscribing witnesses.
